UNITED STATES PATENT OFFICE.

WILLIAM D. COOPER, OF PALMYRA, MISSOURI.

LOADING MACHINE.

Application filed October 17, 1925. Serial No. 63,120.

This invention relates to improvements in loading machines, the general object being the provision of a platform having a grate arranged centrally thereof and supported an appreciable distance above a ground floor upon a wheel frame and having means provided upon its opposite end in associating inclined platforms thereof whereby dredges, scoops and like implements may be drawn up to the main platform and have their contents dumped upon the grate within the platform in order that vehicles run beneath the machine may be readily loaded without the necessity of the vehicle running direct to the point at which the material is first gathered.

Another object of my invention resides in the provision of a detachable ridge bar arranged between the respective front and rear axles of the machines which is adapted for detachable engagement therewith and may be readily and easily removed in order that vehicles may run directly beneath the platform and between the wheels of the machine and be readily loaded with the material gravitating through the grate in the platform.

With the above and other objects in view, the invention further includes the following novel features and details of construction, to be hereinafter more fully described, illustrated in the accompanying drawings and pointed out in the appended claim.

In the drawings:—

Figure 1 is a side elevation of my invention.

Figure 2 is a top plan view of the main platform and grating with an inclined platform associated therewith.

Figure 3 is a longitudinal sectional view taken through the machine illustrating the manner in which the platforms are associated therewith.

Figure 4 is a front elevation of my invention.

Figure 5 is a rear elevation thereof.

Figure 6 is an elevation of reach bar.

Figure 7 is a fragmentary top plan view of the front wheels and axles for the machine with a draw bar connected therewith.

Referring to the drawings in detail, wherein like characters of reference denote corresponding parts, the reference character 10 indicates an elongated frame preferably formed of channel bars and having a floor 11 arranged upon the upper side thereof and defining a rectangular opening 12 centrally

thereof and having its marginal edges supported by a relatively small rectangular frame 13, also being channel bar, the platform, as completed, being supported by long and short rear and front angle bars 14 and 15, respectively. The bars 14 having plates 16 secured to the lower end and terminating in circular end portions 17 for journalling the corresponding outer and opposite end portion of a rear axle 18 having wheels 19 mounted thereon for supporting the rear portion of the machine. The respective lower free ends of the bars 15 having the corresponding and opposite end portions of a spring bolster 20 associated therewith and, in turn, having its intermediate portion associated with the corresponding portions of a sub-bolster 21 through the instrumentality of a bolt 22, while its respective end portions 23 are secured to the upper side of a front axle 24 supporting wheels 25 upon its opposite ends.

The forward side of the front axle 23 having pairs of spaced parallel forwardly disposed plates 26 arranged at spaced intervals in the back of the axle 23 for pivotally associating the corresponding inner end portions of brace rods 27 carried by a draw bar 28 capable of being hitched to a single-tree or the rear end of a tractor.

The forward end of the frame 10 provides spaced parallel apertured ears 29 to receive bars 30 in order that the forward hooked end portions 31 of channel bars 32 having floors 33 arranged upon the upper side thereof may be associated therewith and adjacent the corresponding meeting edges of the floor 11 and arranged at inclinations with respect thereto, as clearly illustrated in Figures 1 and 3, respectively, said inclinations to be made of sufficient length in proportion to height of machine, so as not to exceed an angle of 26 degrees. The rectangular opening 12 defined centrally within the floor 11 and supported by the rectangular frame 13 provides a plurality of plates 34 standing on edge in spaced parallel relation in forming a grate, the purpose of which will be presently apparent.

Bars 34 support a railing 35 extending an appreciable distance above the floor 11 upon the frame 10 for preventing injury to persons upon the floor 11 in pouring the material through the grate provided by the plates 33.

It will thus be noted from the foregoing

description and accompanying drawings that the machine as completed provides a device capable of loading trucks and other vehicles run beneath the frame 10 therefor and be loaded with the material so dumped upon the grate arranged within the floor 11 whereby the necessity of successively handling the material prior to a deposit within the vehicle will be obviated and consequently a material saving in labor. Obviously no connecting means being provided between the respective axles 18 and 23 during the process of loading vehicles beneath the machine, but when it becomes incumbent upon the users of the above entitled invention to move the machine about, it is then necessary to provide a substantially V-shaped bar 36 supporting an apertured plate 37 upon the forward meeting end portions capable of receiving a stud arranged upon the upper side of a plate 39 secured centrally of the length of the front axle 23 through the instrumentality of U-bolts 40, while the respective and opposite end portion of the ridge bar 36 being secured to the upper side of the rear axle

18 through the instrumentality of U-bolts 41. The drawbar, as associated, tending to prevent the frame 10 from collapsing owing to any relative movement of the respective axles.

30

The invention is susceptible of various changes in its form, proportions and minor details of construction, and the right is herein reserved to make such changes as properly fall within the scope of the appended claim.

35

Having thus described my invention, what is claimed is:—

A loading apparatus comprising a frame, a supporting floor carried thereby having a rectangular opening including a grate therein, bars of different lengths depending from said frame, an axle having wheels mounted thereon carried by the longer bars, a bolster carried by the shorter bars, a sub-bolster pivotally mounted upon the aforementioned bolster, an axle and wheels therefor carried by the sub-bolster, and a draw bar carried by the last mentioned axle.

40

In testimony whereof I affix my signature.
WILLIAM D. COOPER.
